UNITED STATES PATENT OFFICE.

WILLIAM B. RUDDICK, OF NEW YORK, N. Y.

CLAMP.

No. 852,681.

Specification of Letters Patent.

Patented May 7, 1907.

Application filed August 1, 1906. Serial No. 328,735.

To all whom it may concern:

Be it known that I, WILLIAM B. RUDDICK, a citizen of the United States, residing at New York city, in the county of New York 5 and State of New York, have invented certain new and useful Improvements in Clamps, of which the following is a specification.

My invention relates to clamps.

It should be understood that, in fire proof 10 building construction the floor sleepers have to be secured to the concrete arches, as they are not, as in ordinary building construction, supported by their ends extending into the walls, the usual way of accomplishing this 15 being by embedding them in the concrete arches, but this way as well as all others known to this applicant are attended with more or less unsatisfactory results and also necessitate the expenditure of considerable 20 time and labor.

My invention therefore has for its object to overcome the above mentioned difficulties by providing a clamp by which anchors for securing the floor sleepers may be grasped and 25 properly inserted and positioned in a soft base, usually green concrete, so that their upper ends project beyond the surface of the base, whereby when the base becomes hard the anchors will be firmly secured therein in 30 the position required to receive the sleeper between them and be driven in said sleepers, thereby insure perfectly level and firm floors.

It has for a further object to provide a device of the character set forth embodying advantages in point of simplicity and inexpensiveness of construction and effectiveness in 35 operation.

In the drawings:—Figure 1 is a vertical sectional view through a concrete arch or 40 base, showing my clamp in the position it assumes when inserting the anchors. Fig. 2 is a plan view of my clamp. Fig. 3 is an enlarged detail vertical sectional view through a concrete arch or base and through one of 45 my clamps showing the clamp in the position it assumes when inserting the anchors. Fig. 4 is an enlarged detail vertical sectional view through a concrete arch or base and through one of my clamps, showing my clamp in the 50 position it assumes when being withdrawn. Fig. 5 is an enlarged detail face view of one of the socketed plates which the upper ends of the anchors engage when grasped by the clamp. Fig. 6 is an enlarged detail edge 55 view of one of the anchors, and Fig. 7 is a fragmentary detail perspective view of a

concrete arch or base, showing sleepers secured in position thereon by the anchors inserted and positioned by my clamp.

In all the figures of the drawings illustrating my invention, like reference characters designate corresponding parts.

Referring to the drawings, the intermediate fixed jaw of the clamp is substantially T shaped in cross-section, embodying a central vertically extending portion 1 provided at its top with lateral horizontally extending portions 2 and 3. The lower end of the portion 1 of this jaw is incased in a suitable covering 4 of sheet metal to protect it from 70 wear and prevent it from sticking to the green concrete. The lateral movable jaws 5 and 6 of the clamp are hung on the portions 2 and 3 respectively of the fixed jaw by suitable spring hinges 7 adapted to normally 75 hold them yieldably in contact with the portion 1 of the fixed jaw and bring their outer faces normally flush with the outer faces of the portions 2 and 3 of the fixed jaw.

To permit the movable jaws to open without engaging the concrete they are made shorter than the portion 1 of the fixed jaw and these jaws are provided with laterally extending handles 8 which afford means for opening them against the action of the 85 spring hinges. To the inner faces of the movable jaws, in staggered relation to one another, are secured pairs of metal plates 9 having right angular shaped sockets 10 adapted to receive the upper ends of the 90 anchors 11 for securing the floor sleepers 12 to the concrete base or arch 13.

To afford means for truing up the clamps preparatory to fully inserting and positioning the anchors in the green concrete, a vertically 95 extending rod 14 is secured in the top of the fixed jaw at about a central point between the anchors in each of the end pairs of plates and these rods are brought into contact with a guide line 15. These anchors preferably 100 embody a straight portion 16 provided at each end with oppositely extending portions 17 and 18 bent over therefrom and having beveled faces 19 to make them pointed for easy insertion into the floor sleepers. 105

The operation of inserting and positioning the sleeper anchors in the green concreted base is as follows: grasp the handles 8 and force the movable jaws 2 and 3 open against the action of the spring hinges, insert the upper ends of the anchors into the sockets in the plates 9, release the jaws allowing them 110

to be closed by the action of the spring hinges, thereby firmly clamping the anchors between the plates thereon and the fixed jaw, place the clamp in an upright position with the lower ends of the anchors resting on the green concrete and the rods 14 against the guide line 15, place the foot on the top of the clamp and press down until the lower end of the part 1 of the clamp contacts with the concrete, thus forcing the anchors down the proper depth in the concrete, then grasp the handles 8 again and open and release the anchors. After the concrete has hardened somewhat thus firmly securing the anchors, the sleepers are placed between the pairs of anchors running in line with one another and the ends of the anchors are driven into the sleepers thus securely fastening them.

The method of securing the sleepers is not herein claimed as it forms the subject of a co-pending application filed by me on the 5th day of April, 1907, Serial Number 366,476.

I do not wish to be understood as limiting myself to the details of construction and arrangement as herein described and illustrated, as it is manifest that variations and modifications may be made in the features of construction and arrangement, in the adaptation of the device to various conditions of use, without departing from the spirit and scope of my invention and improvements. I therefore reserve the right to all such variations and modifications as properly fall within the scope of my invention and the terms of the following claims.

Having now described my invention, what I claim as new and desire to secure by Letters Patent, is:—

1. A clamp for the purpose set forth, embodying an intermediate fixed jaw, lateral movable jaws and means for holding said jaws normally closed, substantially as described.

2. A clamp for the purpose set forth, embodying an intermediate fixed jaw and lateral movable jaws having sockets, substantially as described.

3. A clamp for the purpose set forth, embodying an intermediate fixed jaw, and lateral movable jaws provided with plates having sockets, substantially as described.

4. A device for the purpose set forth, embodying an intermediate fixed jaw, lateral

movable jaws and means for yieldably holding said jaws normally closed, substantially as described.

5. A clamp for the purpose set forth, embodying an intermediate fixed jaw, movable jaws having engaging means and means for holding said jaws normally closed, substantially as described.

6. A clamp for the purpose set forth, embodying an intermediate fixed jaw, movable jaws having engaging means and means for yieldably holding said jaws normally closed, substantially as described.

7. A clamp for the purpose set forth, embodying an intermediate fixed jaw and lateral hinged jaws, substantially as described.

8. A clamp for the purpose set forth, embodying an intermediate fixed jaw, lateral hinged jaws and means for holding said jaws normally closed, substantially as described.

9. A clamp for the purpose set forth, embodying an intermediate fixed jaw, lateral hinged jaws and means for yieldably holding said jaws normally closed, substantially as described.

10. A clamp for the purpose set forth embodying an intermediate fixed jaw, lateral hinged jaws having sockets and means for holding said jaws normally closed, substantially as described.

11. A clamp for the purpose set forth embodying an intermediate fixed jaw having lateral extensions and lateral jaws hinged to said extensions, substantially as described.

12. A clamp for the purpose set forth embodying an intermediate fixed jaw having lateral extensions, lateral jaws hinged to said extensions and means for holding said jaws normally closed, substantially as described.

13. A clamp for the purpose set forth embodying an intermediate fixed jaw having lateral extensions, lateral jaws hinged to said extensions and means for yieldably holding said jaws normally closed, substantially as described.

In testimony whereof, I have signed my name, in the presence of the subscribing witnesses.

WILLIAM B. RUDDICK.
